ART OF FEEDING FINELY COMMINUTED FUEL INTO A COMBUSTION CHAMBER

Filed May 10, 1928

Inventor

Charles M. Bush

By his Attorney

Carrie S. Campbell.

UNITED STATES PATENT OFFICE

CHARLES M. BUCK, OF BROOKLYN, NEW YORK

ART OF FEEDING FINELY COMMINUTED FUEL INTO A COMBUSTION CHAMBER

Application filed May 10, 1928. Serial No. 276,523.

My invention relates to an improvement in the art of feeding finely comminuted fuel into a combustion chamber, and its novelty consists in the steps of the process and the means for carrying out the same as will be more fully hereinafter pointed out.

My process and the means for carrying out the same are particularly adapted for use in connection with the products of my pending 10 United States patent application Serial No. 265,303, filed March 28, 1928 on my improvement in the treatment of coal and other carbonaceous material of a similar nature and in the product produced, but it is also adapted 15 to be used in connection with pulverized coal or fuel prepared by other methods.

In the previous methods and means for feeding finely comminuted fuel to a combustion chamber it has been necessary to use an excess of air and a substantially high pressure with the result that the flame in the combustion chamber varies substantially a large amount of the fuel is not consumed but is wasted and the combustion chamber is excessively heated at certain points so that there is a very substantial loss of heat released and the attendant destruction of the fire chamber.

My process and the means for carrying out the same overcome all of these difficulties, furnishing substantially perfect aeration to the comminuted fuel and conveying the same on a light current of air spread out in a sheet and delivered to the combustion chamber in a sheet the full width of the combustion space, thereby insuring greatly improved combustion and consumption of the fuel and absorption of the heat released without any injury to the fire chamber or loss of fuel.

Referring to the drawing, Figure 1 is a front elevation of my device.

Figure 2 is a vertical cross section through the middle of Figure 1.

Figure 3 is an end view of the agitator.

Figure 4 is a fragment of one end of the agitator, parts being broken away for convenience in illustration.

Figure 5 is a front view of the gate.

Figure 6 is an end view of the same looking 50 in from the right-hand end of Figure 5.

Figures 7 and 8 are details of the air port shutter control.

In the drawing 10 is a fuel container having a fuel feed pipe 11 and an air inlet pipe 12. The fuel container 10 terminates at its lower end in an agitator housing 13 in which is mounted an agitator 14 on a shaft 15 and which has alternately staggered rows of pyramidal agitating members 16 rigidly mounted thereon. A gate 17 having air openings 18 is mounted immediately below an opening 19 at the base of the agitator housing 13 and the gate 17 has toothed lugs 20 adapted to be meshed by gears 21 mounted on shaft 22 which is adapted to be turned or controlled by a wheel or handle 23 rigidly mounted on said shaft 22. A blower cylinder 24 is mounted immediately below the gate 17 and in the same is mounted a rotating blower 25 of usual construction which is rotated on shaft 26. On the shaft 26 are mounted a pair of hanger members 27 and 27a between which is suspended air port shutters 28 by means of which the opening to the blower cylinder 24 may be varied as desired. A passageway 29 the full width of the gate 17 and the opening 19 leads from the blower cylinder 24, gate 17 and opening 19 into the combustion chamber which is not shown, where the fuel is to be consumed.

On one end of the blower shaft 26 is mounted a pulley 30 adapted to be connected up by a belt to the source of power not shown. A gear 31 is rigidly secured to the shaft 26 and a large gear 32 is rigidly secured to an idler shaft 33 so that said gears 32 and 31 mesh and run together. A small gear 34 is also rigidly secured on the idler shaft 33 and meshes with a large gear 35 which is rigidly secured on the agitator shaft 15. The outer end of the hanger member 27 terminates in a wheel or handle 36 by means of which the adjustment of the air port shutters 28 may be adjusted manually as desired.

In operating my device the finely comminuted or pulverized fuel which is fed through pipe 11 into the container 10 passes down through 10 into the agitator housing 13. The agitator 14, by means of the agitating members 16 which pick up and carry

around as agitator 14 rotates the finely comminuted fuel, dropping it into the opening 19. As the blower 25 is operating, induced air is drawn through openings 18 in gate 17 5 and passes through the gate 17, carrying the comminuted fuel as it drops in a portion the complete width of the opening 19 and passageway 29 so that the induced air carries this portion, spreading it in a thin sheet 10 along through the passageway 29 where the air from the blower 25 comes in to carry it along at a slightly more rapid rate, tumbling it and mixing it so that it is thoroughly aerated and delivering it in a suspended sheet 15 to the combustion chamber.

As the blower 25 is rotated by means of the pulley 30, the gear 31 meshing with gear 32 drives the gear 32 and the idler shaft 33 so that gear 34 is also rotated thereby and 20 being in mesh with gear 35 rotates the same whereby the shaft 15 is rotated thereby rotating the agitator 14 as described.

In carrying out my method of feeding finely comminuted fuel to a combustion chamber the comminuted fuel is fed across the complete width of the conveyor passageway, being picked up by a current of induced air and spread substantially into a sheet whereby it is carried into the column of blown 25 air still in a sheet and as it is so carried through the conveyor passageway through tumbling and contact with the surfaces of the side of the conveyor passageway is aerated and fed into a combustion chamber 30 substantially in a sheet and the full width of the combustion chamber and being aerated is combustible as fed, the air pressure, not being sufficient to prevent the aerated comminuted fuel from having time to thoroughly 35 combust in the combustion chamber.

By drawing or removing fuel from the container or source of supply spread out in the form of a sheet or approximately in the form of a sheet into a current of air of approximately the same width the fuel is approximately spread out in a uniform thin sheet as it enters the induced air current and this condition is not disturbed by the blower 45 air current which is merely sufficient to continue the further carrying of the sheet of fuel thoroughly mixed with air to the combustion chamber. The air current is regulated so as to contain such quantities of air as will furnish the necessary oxygen for the thorough 50 combustion of the fuel and the regulation of the air current may be by the carbon dioxide content of the stack gases or by the products of combustion. The delivery of the comminuted fuel into the induced air current spread out in the form of a sheet and the maintaining of this sheet for the entire width of the conveyor passageway right into the full width of the combustion chamber insures 55 thorough aeration and suspension during the entire combustion of the fuel. This

avoids the use of excess air for the driving or carrying of the comminuted fuel and permits the combustion to take place under less pressure than has been possible heretofore and the heat released is permitted to tarry 70 longer whereby it is chiefly absorbed and utilized instead of being blown on through the combustion chamber and up the stack.

The delivery of the comminuted fuel in an approximately uniform sheet into the entire 75 width of the combustion space insures uniform combustion across the entire width of said combustion space thereby securing the releasing of the heat uniformly across the entire combustion chamber which permits of 80 the maximum absorption of said heat.

My method of feeding the comminuted fuel in a sheet the entire width of the combustion chamber permits of the withdrawing of the fuel from the container in the desired quantity varying from a mere film to a fraction of an inch in thickness. Any slight variation in the thickness of the fuel is at once reflected in its combustion. This permits of the most positive and exact regulation of the fuel drawn or removed from the container to meet the heat requirements. It is thus seen that the feeding of the fuel may be properly regulated by a thermostat or through steam pressure or through any other 90 well known heat control method. The quantity of fuel drawn from the container is made to vary to correspond with the variations in the load or amount of heat required whereby 95 perfect feed control is attained and maintained.

I do not limit myself to the particular means disclosed as any equivalent means for carrying out the method described may be used to attain the result described. 100

More nearly perfect results will be secured in carrying out my process if the finely comminuted and suspensive fuel described in my pending application Serial No. 265,303 is used, but my method and means for carrying 110 out the same may be also successfully used with any good quality of pulverized coal or finely comminuted fuel.

The method of burning pulverized coal mixed with the air required for combustion 115 is part of the subject matter of my copending application Serial No. 629,063, filed August 16th, 1932.

I claim:

1. The method of drawing pulverized coal 120 from a container having a discharge orifice which consists in simultaneously blowing a blast of air past said orifice and thereby inducing a current of air past said orifice and between it and the said blast of air, the coal 125 under the influence of gravity and suction, dropping into the resulting air stream of double strata.

2. In combination, a pulverized coal hopper having a bottom discharge orifice, a lat- 130

erally extending conduit into the upper part of which the orifice opens at a point intermediate the ends thereof, a burner at one end of the conduit, means for supplying a blast 5 of air into the opposite end of the conduit in the lower part thereof, a passage in the upper part of said conduit at said opposite end thereof, said passage being open to the atmosphere at one end and having its opposite 10 site discharge end in proximity to said orifice, whereby the said blast of air draws a current of air through said passage which current of air moves past said orifice and between it and the blast of air, and the coal, under the influence of gravity and suction, drops into a 15 stream of air of double strata, one stratum of which moves more slowly than the other, so that mixing occurs in the conduit.

3. In combination, a pulverized coal hopper 20 having a bottom discharge orifice, a laterally extending conduit into the upper part of which the orifice opens at a point intermediate the ends thereof, a burner at one end of the conduit, means for supplying a blast 25 of air into the opposite end of the conduit in the lower part thereof, a passage in the upper part of said conduit at said opposite end thereof, said passage being open to the atmosphere at one end and having its opposite 30 discharge end in proximity to said orifice, whereby the said blast of air draws a current of air through said passage which current of air moves past said orifice and between it and the blast of air, and the coal, 35 under the influence of gravity and suction, drops into a stream of air of double strata, one stratum of which moves more slowly than the other, so that mixing occurs in the conduit; said orifice being a hole through the 40 bottom wall of the hopper.

4. In combination, a pulverized coal hopper having a bottom discharge orifice, a laterally extending conduit into the upper part of which the orifice opens at a point intermediate 45 the ends thereof, a burner at one end of the conduit, means for supplying a blast of air into the opposite end of the conduit in the lower part thereof, a passage in the upper part of said conduit at said opposite end thereof, said passage being open to the atmosphere at one end and having its opposite 50 discharge end in proximity to said orifice, whereby the said blast of air draws a current of air through said passage which current of air moves past said orifice and between it and the blast of air, and the coal, under the influence of gravity and suction, 55 drops into a stream of air of double strata, one stratum of which moves more slowly than the other, so that mixing occurs in the conduit; and means whereby the location of the discharge end of said passage in relation to the orifice may be adjusted.

60 In testimony whereof I affix my signature.
65 CHARLES M. BUCK.
